Primary Examiner — Derrick Holland*Assistant Examiner* — Jennifer O King*(74) Attorney, Agent, or Firm* — Harness, Dickey & Pierce, P.L.C.(57) **CLAIM**

The ornamental design for the electrical current transducer, as shown and described.

DESCRIPTION

FIG. 1 is top front perspective view of a first embodiment of an electrical current transducer showing my new design; FIG. 2 is bottom rear perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof; and

FIG. 8 is a right side view thereof.

FIG. 9 is top front perspective view of a second embodiment of an electrical current transducer showing my new design; FIG. 10 is bottom rear perspective view thereof;

FIG. 11 is a front view thereof;

FIG. 12 is a rear view thereof;

FIG. 13 is a top plan view thereof;

FIG. 14 is a bottom plan view thereof;

FIG. 15 is a left side view thereof; and,

FIG. 16 is a right side view thereof.

The broken lines shown represent unclaimed subject matter and form no part of the claimed design.
